United States Patent Office.

JOHN H. ATWATER, OF OSHTEMO, MICHIGAN.

Letters Patent No. 98,903, dated January 18, 1870.

IMPROVEMENT IN DRAWING-KNIFE.

The Schedule referred to in these Letters Patent and making part of the same.

To all whom it may concern:

Be it known that I, JOHN H. ATWATER, of Osh-temo, in the county of Kalamazoo, in the State of Michigan, have invented a new and improved Drawing-Knife; and I do hereby declare that the following is a full and exact description thereof, reference being had to the accompanying drawings, and to the letters of reference marked thereon—

Figures I and V representing side views;

Figure II, a cross-section;

Figure III, a plan; and

Figure IV showing the blade.

My invention consists of a blade, A, sharpened in different bevels, as shown by the cross-section, Fig. II.

There is a prolongation on each end, provided with four projections, B, C, D, and E, and connected at the extremities by hinge-joints, with two handles, F and G. These are allowed to swing through an angle of one hundred and eighty degrees, but are hindered by the projections B, C, D, and E, from surpassing this angle.

Thus the extreme positions are represented in Figs. I and V.

The object of this, my invention, is to furnish a drawing-knife, which will dispense with the use of two or more knives where different bevels are wanted.

The blade being properly sharpened, this knife contains four different bevels, all of which may be used either by reversing the knife in the hinges, or by passing the right-hand handle into the left hand, and inversely.

As this knife will be, if at all, but a trifle more expensive than others, it presents the double advantage of economy and of greater simplicity.

What I claim as my invention, and desire to secure by Letters Patent, is—

A drawing-knife, composed of the blade A, sharpened in different bevels, and furnished at both ends with prolongations, H I, which are joined by hinges to the handles.

Also, the projections B, C, D, and E, for preventing the handles from closing too far.

JOHN H. ATWATER.
